UNITED STATES PATENT OFFICE.

LOUIS A. UNLAND, OF BEARDSTOWN, ILLINOIS.

GRAVE BOX.

Application filed November 18, 1926. Serial No. 149,162.

This invention relates to grave boxes and it is an object of the invention to provide a device of this kind formed of galvanized sheet iron or the like and which is constructed in a manner to effectively prevent for a protracted period of time the liability of a grave caving in.

It is also an object of the invention to provide a box of this kind which may be readily shipped in a knock-down form or, if desired, may be shipped in assembly with an empty casket housed therein.

The invention consists in the details of construction and in the combination and arrangement of the several parts of my improved grave box whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view in side elevation of a grave box constructed in accordance with an embodiment of my invention;

Figure 2 is an enlarged vertical sectional view taken lengthwise through the structure as illustrated in Figure 1, with the central portion broken away;

Figure 3 is a transverse sectional view taken through the structure as herein disclosed;

Figure 4 is a fragmentary horizontal sectional view illustrating the connection between a side wall and an end wall of the box;

Figure 5 is a fragmentary vertical sectional view taken through the end portion of the lid illustrating the connection between an end plate and the body portion of the lid.

As herein disclosed, my improved box comprises the side walls 1 and the end walls 2 each formed of galvanized sheet iron or the like, the end walls 2 being provided with side flanges 3 whereby the same may be connected to the extremities of the side walls 1 by galvanized stove bolts 4.

The major portions of the side walls 1 and the end walls 2 are transversely corrugated from end to end and the lower marginal portions of each of such walls are rolled outwardly to provide further strengthening means. The upper marginal portions of said

side walls 1 and end walls 2 are unobstructed and adapted to be snugly received within the downwardly facing channels 5 extending along the marginal portions of the lid L.

The lid L is formed of galvanized sheet iron or the like and comprises an arched body portion 6 corrugated transversely from one end to the other, the extremities of said body portion 6 being defined by the inwardly disposed flanges 7 whereby the end lid plates 8 may be secured to the body portion by the galvanized stove rivets 9.

The downwardly facing channels 5 are preferably formed by providing the free marginal portions of the body portion 6 and the end plates 8 with the reverted flanges 10.

The lower marginal portions of the side walls 1 in the assembled box are connected by the cross members or rests 11 substantially in the form of an inverted U. The extremities of each of said members or rests 11 are defined by the upstanding flanges 12 whereby said members or rests may be effectively secured to the lower marginal portions of the side walls 1 by galvanized stove bolts 14.

By the use of stove bolts it is possible to ship my improved grave box in a knock-down form, the stove bolts readily permitting the desired assembly of the box by the casket maker or undertaker. In initially forming the various parts of the box it is to be understood that they have properly punched therein the requisite openings for the proper insertion of the bolts.

My improved box can, if preferred, be shipped in assembled form and if desired with an empty casket housed therein. When so shipped it is preferred that the casket be affixed to the cross members or rests 11 by suitable screws threaded into the bottom of the casket from below the members or rests 11. It is to be understood that such a shipment is to be from the producer to the undertaker or other distributing agent.

Each end wall 2 has suitably affixed thereto the handle members 15 and the opposite end portions of the lid L are also provided with the handles 16.

As hereinbefore described, it is to be noted that the assembled box is bottomless. It is not essential that a box of this kind be provided with a bottom as it is not the purpose to have my improved box any more waterproof than the general type of wooden boxes now used. It is the purpose of my improved

box to keep the filled grave for a protracted period of time from caving in. The corrugations of the various plates together with the reinforcement afforded to the structure by the cross members or rests 11 serve to give to the assembled box pronounced strength capable of withstanding considerable pressure.

If it should be preferred, however, a bottom plate 17 of a size to snugly fit within the lower portion of the assembled box may be employed. This bottom plate when applied contacts from above with the members or rests 11 and is preferably secured thereto by galvanized stove bolts 18.

From the foregoing description it is thought to be obvious that a grave box constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

30 I claim:

1. A grave box comprising side and end walls, the top and bottom of the box being

open, a lid engageable with the upper portions of the walls for closing the top of the box, said walls being of a material height, and rest members interposed between and connected to the lower portions of the side walls of the box, said members being spaced apart in a direction lengthwise of the box, said rest members being substantially in the form of an inverted U in cross section with the free edges of said rest members substantially flush with the lower edges of the walls of the box.

2. A grave box comprising side and end walls, the top and bottom of the box being open, a lid engageable with the upper portions of the walls for closing the top of the box, said walls being of a material height, rest members interposed between and connected to the lower portions of the side walls of the box, said members being spaced apart in a direction lengthwise of the box, said rest members being substantially in the form of an inverted U in cross section with the free edges of said rest members substantially flush with the lower edges of the walls of the box, a bottom wall insertible within the box through the open top and resting from above on the rest members, and means for securing the bottom wall to the rest members.

In testimony whereof I hereunto affix my signature.

LOUIS A. UNLAND.
